UNITED STATES PATENT OFFICE.

ALBERT KRAUTH, OF HAMILTON, OHIO.

MANIFOLDING APPARATUS.

1,225,140.

Specification of Letters Patent.

Patented May 8, 1917.

Application filed February 27, 1913. Serial No. 751,045.

To all whom it may concern:

Be it known that I, ALBERT KRAUTH, a citizen of the United States, residing at Hamilton, in the county of Butler and State 5 of Ohio, have invented certain new and useful Improvements in Manifolding Apparatus, of which the following is a specification.

My invention relates to manifolding machines and in particular to roll or web-holding means.

The contemplated preferable use of the machine is for issuing preprinted forms of express company way-bills, issued for each freight shipment with the preprinted form 15 comprised in multiple numbers in a continuous sheet subdividing the same into definite equal lengths or intervals for consecutive use. One of the sheets contains only a portion of the text form of an original or 20 not a complete duplicate thereof, and in consequence, its width is much less than the remaining sheets contained in the machine. All the sheets or strips are simultaneously 25 and unitarily advanced so that an entry can be recorded in the proper space or position of registry corresponding in all of the sheets.

An object of my invention is to provide a support for rotatably mounting a web of paper between a pair of side frames, comprising a pair of oppositely disposed spring arms, one thereof directly supporting a disk-shaped journaling boss, the second an extension rod in an axial plane with the axis of the opposing disk-shaped journaling boss, 35 with the free end of said rod provided with a disk-shaped journaling boss coincidentally opposite the first-named boss, for supporting a web of paper considerably less in width than the intervening space between the side 40 frames, with both supports accessible from the exterior of the machine for moving the same in a diametrically opposing direction for web insertion or removal.

Another object of my invention is to provide a multiple number of continuous sheets or strips of paper of relatively different width, each sheet correspondingly sub-divided into intervals of equal length, the intervals having areas corresponding for 45 manifolding registry one upon another, for producing a partial manifold record or records of an original entry and when threaded within a machine are capable of being fed or advanced in unity to a point of delivery 50 or discharge from the machine. This is 55 illustrated by assuming that the original

sheet is a merchandise sales receipt containing along one marginal edge opposite each article the price. This original can be used as a bill or statement for the purchase 60 while the duplicate or manifold can be used for a shipment bill of lading, with no disclosure of the price of the goods, in this way a single entry is manifolded for various independent uses and purposes, effecting a 65 great saving of time and avoiding error.

The features of the invention are more fully set forth in the description of the accompanying drawings, forming a part of this specification, in which:—

The figure represents a central vertical section through a manifolding machine containing my improvement.

1 represents the base of the machine, 2, 2, the stationary side frames. 4 represents the 75 writing table, and 5 the margin-frame above the same hingedly mounted to the carbon receptacle 6.

The webs of paper are journaled upon supports substantially as that shown in a 80 prior patent issued to me, No. 925,351, dated June 15, 1909, for supporting the rolls of a length approximately the interior width of the casing, and in general comprise a pair of oppositely disposed spring metal plates, one 85 secured to each of the side frames, having a disk-shaped journaling boss mounted upon the free end of each spring metal plate. The axes of the bosses are in coincident axial plane, with the flange of each disk engaging 90 a side of the web, and the boss thereof projecting into the core of the web.

In the form shown in the figure, one roll support is constructed as above described, in which 20 represents a spring metal plate, 95 having a disk-shaped boss 21 supported upon its free end by a pin 22, said pin being arranged with a hand hold so as to be accessible from the exterior of the casing for disengaging the disk-shaped boss from 100 the web core. The opposite side of the frame has a similar spring metal plate 23, provided with an extension rod 24 rigidly secured to the metal plate 23, and with a hand hold 25 accessible from the exterior of the frame, so 105 as to withdraw the disk-shaped journaling boss 26 from its engagement with the web of the paper. This disk-shaped boss may be rigidly secured to the extension rod 24, or journaled thereon, depending upon the 110 grade of paper of the web.

27 represents an angled extension rod sup-

porting plate secured to the base of the machine to support the free end of said rod to maintain its axis coincident with the axis of the opposing disk-shaped journaling boss. 5 This type of web support offers all the advantages as if the disk-shaped journaling boss were directly mounted adjacent to its spring metal supporting plate, and, therefore, provides a means for supporting a 10 web of paper of a width considerably less than the interior width of the casing, but accessible from the exterior of the casing for web renewal.

A web of manifolding paper is supported 15 in a receptacle 6 disposed in a longitudinal plane with the feed of the paper and secured upon one of the side frames, so as to thread the manifolding paper transversely across the writing table 4 to the rewinding 20 apparatus or mechanism upon the opposite side of the casing from that of the carbon receptacle.

The supply web of carbon paper in the carbon receptacle is restricted from a free 25 rotation by means of the tension plate 37 bearing downwardly upon the periphery of the web, as shown.

Having described my invention, I claim:

1. An autographic register comprising a 30 pair of oppositely disposed apertured side frames, a spring member secured to one side frame extending radially to its aperture, and provided with a journaling boss on its free

end, a spring member on the second side frame extending radially toward the aperture of the side frame, an extension rod secured to said spring member extended toward the opposing spring member and accessible from the exterior through the aperture, and a journaling boss upon the free end of 40 said extension rod axially alining with the aforesaid opposing journaling boss.

2. A machine of the nature disclosed combining a pair of oppositely disposed side frames, a spring metal arm secured to each 45 side frame, one thereof having a disk-shaped journal boss secured to its free end, a lateral extension secured to the second arm provided with a disk-shaped journaling boss in a coincident axial plane with said opposing 50 boss.

3. A machine of the nature disclosed combining a pair of oppositely disposed side frames, a laterally yielding journal on one of said side frames, a spring metal arm 55 on the opposite frame, a disk-shaped journaling boss mounted on said arm remotely therefrom, and a rigid bearing slidably supporting the axis of said boss.

In testimony whereof, I have hereunto set 60 my hand.

ALBERT KRAUTH.
